UNITED STATES PATENT OFFICE.

JAMES A. LOYSTER, OF CAZENOVIA, NEW YORK.

CAP FOR MILK-BOTTLES AND SIMILAR RECEPTACLES.

1,346,757.

Specification of Letters Patent. Patented July 13, 1920.

Application filed December 29, 1915. Serial No. 69,218.

To all whom it may concern:

Be it known that I, JAMES A. LOYSTER, a citizen of the United States of America, and resident of Cazenovia, in the county of 5 Madison, in the State of New York, have invented new and useful Improvements in Caps for Milk-Bottles and Similar Receptacles, of which the following, taken in connection with the accompanying drawings, is 10 a full, clear, and exact description.

This invention relates to certain improvements in caps for milk bottles and similar receptacles, and refers more particularly to stoppers of the circular paste-board disk 15 type and to the finger-piece attached thereto for removing the same from the mouth of the bottle.

These disks are usually made of comparatively thin flat cardboard or equivalent comparatively inexpensive material specially treated to render them impervious to moisture and are usually stacked one upon the other in columns to be displaced one by one and forced under pressure into the mouths 25 of successive bottles with sufficient friction to be self-retaining.

It, therefore, becomes necessary to apply the finger-pieces to the caps in such manner that all portions thereof will lie within the 30 planes of opposite faces of the disks when displaced from the stack and applied to the bottle, and at the same time leaving portions thereof accessible for upward deflection from the upper surface of the disk for 35 engagement with the fingers and facilitating the removal of the cap.

I am aware that many devices have been proposed for this purpose, but have discovered that a comparatively thin flexible 40 wire of non-corrodible material properly applied to the cap may be more easily embedded in the surfaces thereof under pressure than metal plates and similar devices, and that when applied to the caps in the 45 manner hereinafter described, they afford a more convenient and reliable means for removing the caps from the bottles than has heretofore been practised.

The main object, therefore, of my present 50 invention is to provide each cap with a finger-piece loop of comparatively fine non-corrodible wire having its ends suitably attached to the disk at or near the edge thereof so that all portions thereof will normally 55 lie within the planes of opposite faces of the cap, and at the same time permitting the

main body thereof to be deflected by the finger at an angle to the adjacent surface whereby the loop may be used as a means for withdrawing the cap from the bottle. 60

Another object is to attach the loop to the cap in such manner that all portions thereof will lie wholly within the marginal edges of said cap.

A further object is to pass the ends of the 65 loop through the cap and to clench them in spaced relation against the inner face thereof while the main body normally lies against the outer face.

A still further object is to deflect the 70 terminal ends of the loop laterally out of alignment with the adjacent arms of such loop so as to engage the inner face of the stopper at points some distance to one side 75 of the portions of the outer face engaged by the adjacent arms of the loop so that when said arms and terminal ends are pressed into the corresponding faces of the cap, the depressions formed therein will be out of alignment, thereby avoiding any 80 liability of materially weakening the portion of the cap to which the ends of the loop are attached.

Other objects and uses relating to specific 85 parts of the device will be brought out in the following description.

In the drawings—

Figures 1 and 2 are opposite face views of my improved bottle cap in which the finger-piece is shown in its normal position flat 90 against the surface of the cap, the dotted lines in Fig. 1 indicating the position which the finger-piece assumes when adjusted for withdrawing the cap.

Fig. 3 is an enlarged sectional view 95 through a portion of the cap taken on line 3—3, Fig. 1, the dotted lines for the finger-piece indicating the position it assumes when adjusted for withdrawing the cap.

The cap comprises a substantially flat circular disk —A— of comparatively stiff cardboard or equivalent inexpensive material and a finger-piece —1— of fine non-corrodible wire suitably secured in a manner hereinafter described to the cap to be 105 used in withdrawing the cap from the bottle when desired.

The disk —A— is, of course, impervious to moisture and may be made of any diameter to fit tightly within the mouth of the 110 bottle into which it is usually forced under pressure and retained by friction.

The wire finger-piece —1— is preferably made in the form of a loop of sufficient size to permit the insertion of the finger therein and has its opposite ends arranged in spaced 5 relation and inserted from the front through the disk —A— at —a— near, but preferably within, the marginal edge of said disk and some distance beyond the rear or under side thereof, whereupon the main body of 10 the loop at the front side of the disk and the terminal ends as —2— at the rear side are bent flatwise against the corresponding faces of the disk and are subjected to sufficient pressure to embed the main body of 15 the loop and terminal ends into said faces so that all portions of the wire will lie wholly within the planes of opposite faces of said disk.

Prior to the pressing of the front and rear 20 portions of the finger-piece flatwise against opposite faces of the disk, the terminal ends —2— are deflected to one side (preferably toward each other) of the lines of extension 25 of the overlying arms of the loop and are, therefore, disposed at an angle to said arms so as to engage portions of the disk at one 30 side of that engaged by the arms to avoid weakening of the disk at the points of attachment of the finger-piece, as would be the case if the terminal ends —2— were in alignment with the over-lying arms of the loop.

This angular disposition of the terminal 35 ends of the loop causes them to act as fulcrums engaging the solid portions of the disk some distance from the apertures —2— and about which the finger-piece may turn when adjusting it for use in the operation of withdrawing the stopper, as shown more clearly 40 in Fig. 3.

Furthermore, it facilitates the bending over of the portions of the wire against opposite faces of the disk, as for example in passing the disk between pressure rollers by 45 which the wire of the entire loop or finger-piece is embedded in the disk wholly within or coincident with the opposite faces of such disk.

This leaves both faces of the disk, including the finger-piece, substantially flat and 50 smooth so that the disks may be stacked one upon the other in close juxtaposition and fed one by one, usually from the bottom, into registration with the mouth of the bottle and plunger (not shown), by 55 which the cap is forced in place.

It will be observed that the terminal ends of the loop at the back of the disk are disposed to one side of (preferably at the inner side) of a straight line between the apertures 60 —2—, as otherwise if they were in a direct line between said apertures, the main body of the loop would tend to turn about the axes of said terminal ends in the operation of pressing it over and upon the top face of the 65 disk, and it would be more or less liable to tear the fiber of such disk, but this is avoided by disposing said terminal ends at an angle to said line and also at an angle to the corresponding arms of the loop. 70

What I claim is:

A bottle stopper comprising a circular disk and a wire finger loop lying flatwise against the upper face of the disk and having its ends passed through spaced apertures in said disk and engaged with the underside of the disk at points between a straight line drawn through the apertures and the closed end of the loop and out of alignment with portions of the arms which 80 engage the upper face of said loop, the main body of said loop at one side of the disk and the ends thereof at the opposite side of the disk being normally embedded flatwise in the corresponding sides of said disk substantially 85 coincident with the surfaces of said sides whereby the disks may be stacked one upon the other with their adjacent faces in close contact throughout their area. 75

In witness whereof I have hereunto set 90 my hand this 23d day of December, 1915.

JAMES A. LOYSTER.
